UNITED STATES PATENT OFFICE

137,051

DESIGN FOR A SADDLE SEAT COVER

Arch M. Hughes, Natchez, Miss.

Application July 20, 1943, Serial No. 110,712

Term of patent 7 years

To all whom it may concern:

Be it known that I, Arch M. Hughes, a citizen of the United States, residing at Natchez, in the county of Adams and State of Mississippi, have invented a new, original, and ornamental Design for a Saddle Seat Cover, of which the following is a specification, reference being had to the accompanying drawing, forming part thereof.

I claim:

The ornamental design for a saddle seat cover, as shown.

ARCH M. HUGHES.
